US00D730375S

(12) **United States Design Patent**
Philopoulos

(10) **Patent No.:** **US D730,375 S**
(45) **Date of Patent:** **** May 26, 2015**

(54) **COMPUTER DISPLAY SCREEN AND PORTION OF A COMPUTER DISPLAY SCREEN WITH A GRAPHICAL USER INTERFACE**

(71) Applicant: **KARL STORZ GmbH & Co. KG**, Tuttlingen (DE)

(72) Inventor: **Alexandros Philopoulos**, Zurich (CH)

(73) Assignee: **KARL STORZ GmbH & Co. KG**, Tuttlingen (DE)

(**) Term: **14 Years**

(21) Appl. No.: **29/443,565**

(22) Filed: **Jan. 18, 2013**

(57) **CLAIM**

The ornamental design for a computer display screen and portion of a computer display screen with a graphical user interface, as shown and described.

DESCRIPTION

The FIGURE is a front view of a computer display screen and portion of a computer display screen with a graphical user interface showing the invention.

The broken lines shown in the drawing represent portions of the graphical user interface that form no part of the claimed design. The computer screen display and portion of a computer screen shown in broken lines form no part of the claimed design.
